A. DINKLAGE
ANCHORING DEVICE
Filed April 4, 1924

FIG. 1.

FIG. 2.

INVENTOR

AUGUST DINKLAGE

BY

Joseph E. Layton

ATTORNEY

UNITED STATES PATENT OFFICE.

AUGUST DINKLAGE, OF EAST ORANGE, NEW JERSEY.

ANCHORING DEVICE.

Application filed April 4, 1924. Serial No. 704,174.

To all whom it may concern:

Be it known that I, AUGUST DINKLAGE, a citizen of the United States, and a resident of East Orange, in the county of Essex and State of New Jersey, have invented a certain new and useful Improvement in Anchoring Devices, of which the following is a specification.

This invention relates to anchoring devices and has more special reference to devices for checking the creep of track rails.

The object of the present invention is to provide a simplified check which can be easily applied, economically maintained in operative position and which will effectually check the creep of the rail.

One phase of the present invention resides in the provision of a single piece check which is adapted to lie flat against a tie so that adequate support is afforded to it which has an offset portion adapted to lock with the rail base and which can be sprung to operative position on the rail on vertical movement of the check.

While the patent to Henggi #1,167,299 shows a creep check device which consists of a single bar having a portion thereof bent in such a manner as to provide a curved wedging surface which tangentially abuts against the rail base, nevertheless the structure shown in this patent can not be sprung to operative position on the rail by vertical movement of the check, but requires a complicated lateral manipulation of the check to place it in position.

Another phase of the present invention resides in the provision of a check end adapted to be hooked over one edge of the rail base and rotated on vertical movement of the rest of the check, the rotation of the hook end locking the check to the rail.

The patent to Warr #1,254,634 shows a structure which has an end hooked over the rail and a yoke which is bowed rearwardly, the yoke, however, presenting but relatively small surface contact with the tie.

Other phases of the invention will become apparent from an inspection of the specification and drawing.

While one embodiment of the present invention is disclosed in the drawing, it is to be understood that this embodiment merely serves as an illustration of the underlying principles of the invention so that they may be readily comprehended by those skilled in the art and is not intended as limiting the

invention to the specific form disclosed therein.

In said drawings:—

Fig. 1 is a side elevation of the invention and

Fig. 2 is a top plan view.

Continuing now by way of a more detailed description, a rail check or anchor indicated in its entirety by A and consisting of a single bar of somewhat resilient material is adapted to be applied to a track rail B of the conventional type. One end of this check A comprises a hook shaped end C, having opposed jaw faces C' and C'' which are spaced apart a sufficient distance to receive the edge of the rail flange and yet located sufficiently close together so that the jaws C' and C'' will lock with the rail on rotation of the end C. The reentrant portion of the hook end C is also of sufficient depth so that an appreciable portion of the rail edge is engaged to obviate any danger of damaging the rail. In order to accomplish the rotation of the end C and the locking of the check to the rail the lower leg or jaw face C'' of the hook end is carried downwardly or bent away from the rail base and forming at the bent portion a ridge or fulcrum D, which is adapted to abut against the rail base when the check is in applied position. The extended portion of the downwardly bent part of the jaw face C'' forms a yoke E which serves among other purposes as a lever arm to rotate the hook end C and clamp the rail edge between the jaw C' and the fulcrum D when the yoke E is carried upwardly. In order to facilitate the application of the check to the rail and to economize material the yoke E is bowed in the manner shown, thereby bringing the end of the yoke remote from the hook end C into close proximity with the rail base and at the same time providing an easily manipulated portion between the opposed rail engaging ends to allow the ends to be spread for the purpose of seating the rail in the check. The end of the bowed portion or yoke E opposite to the rail engaging jaw C has an upstanding arm or latch member F with a reentrant part or rail receiving jaw G, which is adapted to receive and seat one side of the rail base the seating of the rail base in the jaw G locking the fulcrum D against the rail base. The inner face of the arm F is in turn inclined in the manner indicated to

form a cam face H for preliminary engagement with the rail and to spring the jaw outwardly when an upward pressure is applied to the bowed yoke as will be readily apparent from an inspection of the drawing. The distance between the lower edge of this cam face H and the effective rail receiving recess in the hook end C is less than the width of the rail base so that after the rail base has been snapped downwardly over the lower edge of the cam face and seated in the indent the separation of the check and rail under ordinary operating conditions is impossible, the jaw faces C' and C'' firmly locking the check to the rail and when abutting against a stationary part of the road bed effectually checking creep.

In applying the check to the rail, the end C is first hooked over the rail base edge and the arm F initially brought to such position that the rail base edge engages the cam face H. A crow bar or other instrument capable of exerting sufficient leverage is then placed under the bowed yoke E, and the bowed yoke pressed upwardly. This upward pressure against the yoke in conjunction with the pressure exerted by the rail edge against the cam face H slightly straightens the yoke, permitting the jaws G and C to spread apart sufficiently to allow the rail base to seat itself in the indent or jaw G, in which position the offset or fulcrum D is firmly clamped against the rail base. In removing the check, if such removal should be found desirable, a crow bar might be applied to the cam face H, the rail head being used as a fulcrum and the check "sprung off" the rail base.

It is claimed:—

40 1. A rail anchor comprising a resilient yoke having one face adapted to lie flat against a tie and having a ridge which when in operative position is adapted to contact with the bottom of a rail, and opposed base engaging jaws thereon, one of which is adapted to be hooked over one side of the rail base and the other of which is adapted on upward movement thereof to be sprung over the opposite edge of the rail base.

50 2. A rail anchor comprising a rail base engaging jaw adapted on rotation thereof to clamp the base and means comprising a downwardly bowed resilient yoke when in operative position to lock the rail base engaging jaw in clamping position on upward movement of the yoke.

60 3. A rail anchor comprising a rail base engaging jaws adapted on rotation thereof to clamp the base and means comprising a downwardly bowed resilient yoke adapted to lie flat against a tie to lock the rail base engaging jaw in clamp position on upward movement of the yoke.

65 4. A rail anchor comprising a rail base engaging jaw adapted on rotation thereof

to clamp the base and means comprising a downwardly bowed resilient yoke adapted to lie flat against a tie and having a rail base engaging indent to lock the rail base engaging jaw in clamping position on upward movement of the yoke. 70

5. A rail anchor comprising a resilient yoke having an offset adapted to contact with the bottom of the rail, a downwardly bowed portion and opposed base clamping jaws thereon, the jaws being adapted to be spread by upward movement of the bowed portion. 75

6. A rail anchor comprising a resilient yoke having a downwardly bowed portion 80 when in operative position and opposed base clamping jaws thereon, the jaws being adapted to be spread by upward movement of the bowed portion.

7. A rail anchor comprising a rail base 85 engaging jaw adapted on rotation thereof to clamp the base, a downwardly bowed resilient yoke portion when in operative position and an opposed jaw adapted to engage the opposite side of the rail base, the 90 jaws being adapted to be spread on upward movement of the bowed portion.

8. A rail anchor comprising a rail base 95 engaging jaw adapted on rotation thereof to clamp the base, a downwardly bowed resilient yoke portion when in operative position and an opposed jaw having an upward cam face for preliminary engagement with the rail base, the upward movement of the cam face against the rail edge 100 spreading the jaws to permit insertion of the rail.

9. A rail anchor comprising a rail base 105 engaging jaw adapted on rotation thereof to clamp the base, a downwardly bowed resilient yoke portion and an opposed jaw having an upstanding cam face sloping toward the center of the anchor for preliminary engagement with the rail base, the distance between the lower edge of the cam 110 face and the inner face of the base engaging jaw being less than the width of the rail base.

10. A rail anchor comprising a rail base 115 engaging jaw adapted on rotation thereof to clamp the base, a downwardly bowed resilient yoke portion and an opposed jaw having an upstanding cam face sloping toward the center of the anchor for preliminary engagement with the rail base, a rail 120 base engaging indent below said cam face the distance between the lower edge of the cam face and the inner face of the base engaging jaw being less than the width of the rail.

11. A rail anchor comprising a rail base 125 engaging jaw adapted on rotation thereof to clamp the base and means comprising a downwardly bowed resilient yoke to lock the rail base engaging jaw in clamping position,

the straightening of the yoke causing the jaws to spread to a position to receive the rail.

12. A rail anchor comprising a yoke adapted to take a position flat against a tie and a rail base engaging jaw adapted on upward movement thereof to clamp the base.

13. A rail anchor comprising a yoke adapted to take a position flat against a tie and a rail base engaging jaw adapted to be hooked over one side of the rail base, and locked thereto on upward movement of the rest of the check.

14. A rail anchor comprising a yoke adapted to take a position flat against a tie, a rail base engaging jaw adapted to be hooked over one side of the rail base and locked thereto on upward movement of the rest of the anchor and means to lock the end remote from the jaw in position at the end of the upward movement.

15. A rail anchor comprising a rail base engaging jaw, a portion of the anchor being offset to form a fulcrum and means to rotate the rail base engaging jaw about the fulcrum and means to lock the jaw in rotated position the fulcrum being brought to a position where it bears against the rail base on rotation of said jaw.

16. A rail anchor comprising a rail base

engaging jaw, a portion of the anchor being offset to form a fulcrum, a downwardly bowed yoke extending from the fulcrum and means at one end of the bowed yoke to lock 35 the yoke and fulcrum to the rail base.

17. A rail anchor comprising a rail base engaging jaw, a portion of the anchor being offset to form a fulcrum, a downwardly bowed yoke extending from the fulcrum, an 40 upstanding cam face for preliminary engagement with a rail base edge and a rail base engaging indent located below the cam face.

18. A rail anchor comprising a yoke 45 adapted to take a position flat against a rail, a cam face and a rail base engaging indent below the cam face.

19. A rail anchor comprising opposed rail base engaging jaws, one of said jaws having 50 an upstanding cam face for preliminary engagement with the rail base and a bowed yoke connecting the jaws.

20. A rail anchor comprising a yoke adapted to take a position flat against a tie, 55 and a rail base engaging jaw having an upstanding cam face above the jaw for preliminary engagement with the rail edge.

Signed at the city of New York in the county of New York, and State of New 60 York, this 24th day of March, 1924.

AUGUST DINKLAGE.
